UNITED STATES PATENT OFFICE

FERNAND TOURTOIS, OF NEW YORK, N. Y., ASSIGNOR TO COTY, INC., OF NEW YORK,
N. Y., A CORPORATION OF DELAWARE

BRUSH

Application filed July 23, 1929. Serial No. 380,367.

This invention relates to improvements in brushes and more particularly hand brushes.

A particular object of the invention is the provision of a nail or hand brush, compact in design, and having an abbreviated handle, the handle being provided with an opening, the purpose of which will be hereinafter explained.

Further objects of the invention will be apparent from the specification and drawings in which

Fig. 1 is a perspective view of my improved brush in operative position.

Fig. 2 is a top plan view of the handle.

Fig. 3 is an end elevation.

A denotes the top and handle of the brush, preferably made of celluloid, or similar material, the tufts of fibre being inserted on the underside of said body and being designated

B. The extension of the handle has its end constituted by three sides of a hexagon, the other sides of the said hexagon merging into the body of the handle. At the end of the handle is the circular opening C into which a finger of the operator is insertable for the purpose of holding the brush in a fixed position, and at the same time securing the maximum effect when the fibres are manipulated over the fingers.

The illustration shown in the drawing is larger than the most convenient size of the nail brush itself, and it is apparent that in small sizes of the brush it is easier to manipulate same with the finger through the opening C rather than by holding the top and body of the brush with a number of fingers, as no slipping of the brush is possible when same is held through said opening.

It is apparent that changes may be made in the shape of the handle without departing from the spirit of the invention.

Having fully described my invention what I claim is:

1. A hand brush comprising a handle, a series of brush members inserted on the underside of said handle, said handle terminating in an extension having a finger opening therein, the finger opening being closely adjacent the series of brush members.

2. In a nail brush, a handle, brush mem-

bers inserted on the underside of said handle at one end thereof, the opposite end of said handle being enlarged and providing a circular opening in which a finger is insertable and by which the said brush may be manipulated.

In testimony whereof I affix my signature.
FERNAND TOURTOIS.
